UNITED STATES PATENT OFFICE.

FRANK X. KRABACH, OF FORT WAYNE, INDIANA.

NEWSPAPER-FILE.

SPECIFICATION forming part of Letters Patent No. 776,853, dated December 6, 1904.

Original application filed March 24, 1903, Serial No. 149,304. Divided and this application filed March 14, 1904. Serial No. 198,102. (No model.)

To all whom it may concern:

Be it known that I, FRANK X. KRABACH, a citizen of the United States, residing at Fort Wayne, in the county of Allen and State of Indiana; have invented new and useful Improvements in Newspaper-Files, of which the following is a specification.

My invention pertains to files for newspapers and the like; and it has for its object to provide a simple, inexpensive, and convenient file embodying such a construction that while a newspaper may be readily secured thereon and as readily removed therefrom, when desired, there is no liability of the newspaper becoming casually disconnected.

With the foregoing in mind the invention will be fully understood from the following description and claims when taken in connection with the accompanying drawings, forming part of this specification, in which—

Figure 1 is a side elevation of my novel file; Fig. 2, a top plan of the same; Fig. 3, a longitudinal central section with the retaining-rod in elevation, and Fig. 4 an enlarged detail section of the forward end of the file.

Similar letters designate corresponding parts in all of the views of the drawings, referring to which—

A is the bar of my improved file, which is preferably, though not essentially, of wood and circular in cross-section. The said bar has a socket *a* adjacent to one end and a groove *b*, which communicates with the socket, and it also has the latter end beveled, as indicated by *c*, and provided with a kerf or depression *d*, which communicates at one end with the groove *b*, as shown. When the bar A is of wood, I provide the end *c* thereof with a metallic or other suitable reinforcement, the purpose of which is to prevent undue wear of the wood when the head of the retaining-rod, presently described, is sprung into and out of engagement with said head. This reinforcement in the present embodiment of my invention is a metallic staple *e*, embedded in the end *c* of the bar and extending across the depression *d*. When, however, the bar A is of metal tubing, as may sometimes be the case,

the metal reinforcement may of course be dispensed with.

B is a resilient rod, preferably of metal, which normally rests in the groove *b* of bar A and has for its purpose to retain a newspaper thereon. This rod has an angular end *f*, seated in the socket *a* of bar A, and at its opposite and free end it is provided with a rounded head *g*, which by engaging the beveled end *c* of bar A is enabled to hold the rod in groove *b*. The head *g* is preferably in the form of a ring, as shown, this to better adapt the file for use on the newspaper-rack constituting the subject-matter of my contemporary application, filed March 24, 1903, Serial No. 149,304, of which this application is a division.

C is a handle having a socket *h*, which receives one end of the bar A. The said handle is secured on the bar through the medium of a ferrule *i* and a diametrical pin *j* or other means, and it serves to hold the angular end *f* of the rod B in the socket *a* of the bar, and thereby precludes casual disconnection of the rod from the bar, while permitting of the free end portion of the rod being sprung into and out of engagement with the bar.

In the practical use of my novel file it will be observed that when the rod B is placed in the bight or fold of a newspaper while the head *g* is disengaged from the beveled end *c* of bar A and said head *g* is sprung into engagement with said end *c* the newspaper will be held to the bar A without liability of casual disconnection or disarrangement. When, however, the head *g* of rod B is sprung out of engagement with the end *c* of bar A, the newspaper may be readily removed and a fresh paper put in its place. It will also be observed that by grasping the handle C of the file a person is enabled to conveniently hold a newspaper while reading the same.

It will be readily appreciated from the foregoing that with all of its advantages my novel file is simple and inexpensive and embodies no delicate parts such as are likely to get out of order after a short period of use.

I have entered into a detailed description

of the construction and relative arrangement of the parts embraced in the present and preferred embodiment of my invention in order to impart a full, clear, and exact understanding of the same. I do not desire, however, to be understood as confining myself to such specific construction and relative arrangement of parts, as such changes or modifications may be made in practice as fairly fall within the scope of my invention as claimed.

Having described my invention, what I claim, and desire to secure by Letters Patent, is—

1. A newspaper-file comprising a bar having a beveled end, and a resilient rod connected at one end to the bar, and having a rounded head arranged to be sprung into and out of engagement with the beveled end of the bar.

2. A newspaper-file comprising a bar, of wood, having a beveled end, and a metallic reinforcement for the same, and a resilient rod connected at one end to the bar, and having a rounded head arranged to be sprung into and out of engagement with the beveled end of the bar.

3. A newspaper-file comprising a bar having a beveled end, and a resilient rod connected at one end to the bar, and having a ring

arranged to be sprung into and out of engagement with the beveled end of the bar.

4. A newspaper-file comprising a bar having a longitudinal groove, and a beveled end, and a resilient rod connected, at one end, to the bar, disposed in the groove thereof, and having a rounded head, at its opposite end, arranged to be sprung into and out of engagement with the beveled end of the bar.

5. A newspaper-file comprising a bar having a beveled end, a socket adjacent to its opposite end, and a longitudinal groove extending from the socket to the beveled end, a resilient rod arranged in the groove of the bar, and having an angular end portion seated in the socket of the bar, and a rounded head arranged to be sprung into and out of engagement with the beveled end thereof, and a handle secured on the bar, over the angular end portion of the rod.

In testimony whereof I have hereunto set my hand in presence of two subscribing witnesses.

FRANK X. KRABACH.
